UNITED STATES PATENT OFFICE.

HUGO HESS, OF GALVESTON, TEXAS.

DESIGN FOR A BOTTLE-HOLDER.

SPECIFICATION forming part of Design No. 34,499, dated May 14, 1901.

Application filed April 20, 1901. Serial No. 56,772. Term of patent 7 years.

To all whom it may concern:

Be it known that I, HUGO HESS, a citizen of the United States, residing at Galveston, in the county of Galveston and State of Texas, 5 have invented and produced a new and useful Bottle-Holder, of which the following is a specification.

Referring to the accompanying drawings, Figure 1 shows a bottle constructed in accordance with my invention. Fig. 2 is a section of the same on the line 2 2.

In the drawings, A indicates a plurality of holders or receptacles essentially cigar-shaped in general form, each holder comprising a lower portion A' and an upper portion 15 A² A³, indicating the dividing-mark.

B indicates a band surrounding the sec-

tion A', and C indicates a band surrounding the section A², said bands having the representation of bows B' and C', respectively. 20 Each lower section is intended to receive a bottle of cologne or other substance, and the neck is intended to project into the upper section or cover.

Having thus fully described my invention, 25 what I claim as new, and desire to secure by Letters Patent, is—

The design for a bottle-holder, substantially as shown and described.

HUGO HESS.
